FIG. 1 is a front perspective view of an embodiment of a combination toothbrush and tongue scraper;

FIG. 2 is a back perspective view thereof;

FIG. 3 is a front elevation view thereof;

FIG. 4 is a back elevation view thereof;

FIG. 5 is a first side elevation view thereof;

FIG. 6 is a second side elevation view thereof;

FIG. 7 is a first end view thereof;

FIG. 8 is a second end view thereof;

FIG. 9 is a front perspective view of an alternate embodiment of the combination toothbrush and tongue scraper;

FIG. 10 is a back perspective view thereof;

FIG. 11 is a front elevation view thereof;

FIG. 12 is a back elevation view thereof;

FIG. 13 is a first side elevation view thereof;

FIG. 14 is a second side elevation view thereof;

FIG. 15 is a first end view thereof; and,

FIG. 16 is a second end view thereof.

The broken lines, where shown in the drawing figures, illustrate environmental structure and form no part of the claimed design.
